The ornamental design for a wood-type head for a golf club, as shown.

DESCRIPTION

FIG. 1 is a perspective view showing the front and top sides of a wood-type head for a golf club embodying the new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is an enlarged fragmented sectional view taken on the line 8—8 of FIG. 4.
